UNITED STATES PATENT OFFICE.

JOSEPH ZANALETTI, OF ST. CLAIR HEIGHTS, MICHIGAN.

GASOLENE AVIATION ROTARY MOTOR.

1,288,368.

Specification of Letters Patent.

Patented Dec. 17, 1918.

Application filed October 15, 1917. Serial No. 196,684.

To all whom it may concern:

Be it known that I, JOSEPH ZANALETTI, an Italian subject, and resident of the village of St. Clair Heights, county of Wayne, and State of Michigan, have invented a certain new and useful Gasolene Aviation Rotary Motor; and I do hereby declare that the following is a full, clear, and exact description thereof, reference being had to the accompanying drawing, and to the letters of reference marked thereon, making a part of this specification.

My invention relates to improvements in internal combustion engines and has especial reference to engines of this character, in which a plurality of radially disposed cylinders and heads are caused to rotate bodily about a relatively stationary shaft.

One of the objects of my invention is to provide improved valves and valve-operating mechanism, operable with respect to a relatively stationary part, and movable by the bodily rotation of the cylinders, in proper cyclic time relation with the reciprocating pistons, in such manner as to do away entirely with the necessity for an auxiliary valve-operating shaft.

My engine is especially well adapted for use with aeroplanes. The rotation of the cylinder heads and the cylinder structures operate as a counter-balancing regulator for the engine, and the outer surfaces, being thus forcibly brought into contact with the surrounding atmosphere, the air will carry away sufficient heat without the necessity of providing other means for cooling the cylinders of the engine.

In the accompanying drawings forming a part hereof,

40 Figure 1 shows a plan view in section, of four spaced-apart cylinders, of a multiple cylinder engine, set up radially around the engine shaft, without including all of the intervening cylinders, to show the order of motion of the rotating parts.

Fig. 2 is a view showing the cylinder heads at right angles to the showing of Fig. 1.

In both views the same reference characters are employed to indicate similar parts.

The four cylinder heads A are radially disposed with reference to the shaft K and are secured to a central cylinder structure, such as the cylinders of the engine, that ro-

tate about the shaft. When the cylinder heads are employed with a corresponding number of cylinders of an engine, these cylinder heads are adapted to be attached to and supported by the out-board ends of the cylinders. Each of the cylinder heads 55 is axially bored, the bore of which is tapering to accommodate a hollow, correspondingly tapering rotary valve E. The valve is provided with one large port F, more clearly shown in Fig. 1, and exhaust and 60 intake ports, B and C, respectively, are provided in the walls of the cylinder heads. These ports are located 90 degrees from each other. Each of the tapered, hollow valves is provided with an axially projecting tapered boss which passes through the 65 end of the respective cylinder heads. A valve-operating plate G is provided with an inturned flange near its axis, overlying the tapered projecting hub of the valve and is 70 secured to the valve by the nut O. The cylinder head, proper, may be secured to the end of the cylinder, in any convenient manner, as shown. The cylinders do not constitute any part of my invention, therefore, 75 only a fragment of each cylinder is indicated. The internally threaded nut P may be employed in its engagement with threads Q that are made on the outside end of the cylinder to hold the head in place.

It will now be seen that the plate G is the means for rotating the valve E. The plate G is provided, on its inner surface, with an annular groove, with which the balls L engage. In said grooves there are four uniformly arranged spaced apart and oppositely disposed depressions, into which the balls pass when the plate G has been moved to its proper position, so as to temporarily hold it and properly to dispose it to prevent 95 its disturbance until the plate is again positively moved. The balls L are each placed in a cavity M, in four hollow bosses uniformly disposed around the axis of the valve. Springs N in said cavities yielding 100 press the balls against the inner surface of the plate. The springs N tend to hold the balls in the groove and depressions and at the same time cause yielding, but close contact, between the inner bore of the 105 cylinder head and the outer tapered surface of the valve. In the operation of the valve the arrangement is such that the plate

G will be rotated one revolution to every two revolutions of the cylinders, in a manner apparent to persons skilled in the art.

A stationary spider H, having two arms 5 projecting toward the rotatable cylinder heads is provided, and on each arm there is a valve-moving projection I and J. This spider is fixed to the relatively stationary engine shaft and therefore is non-rotatable 10 with respect to the cylinders and cylinder heads. It may, however, be rotatably adjusted on the shaft K to change the time of valve operation.

A plate G is provided with four projection shoulders 1, 2, 3 and 4, giving the plate 15 the general shape of a swastika. As the cylinder and cylinder heads rotate the shoulders engage the projections I and J, respectively, and rotate the valve one-quarter of a revolution by each engagement.

The cylinder heads A are each provided with a valve port B for the exhaust gases, and a valve port C for the intake charges, and a pocket and opening D for a spark plug. 25 This opening is opposite to the intake port C, or 180 degrees removed therefrom. The intake and exhaust ports are closed and opened in proper cyclic relation by the rotation of the tapered, hollow, rotary valve 30 E, which is moved, as heretofore stated, by the plate G in its contact with the relatively stationary projections I or J, when the cylinders are bodily rotated around the shaft K. By this arrangement, proper cyclic operation 35 of the valves is accomplished, without the necessity of providing a special valve shaft for the purpose as usual in engines of this character.

The order of firing and exhausting the 40 charges, in the respective cylinders, may be arranged to suit conditions to be imposed by the designer and the adjustment of the cyclic time at which said operations may take place can be changed by the relative rotation of the spider 8 with respect to the stationary shaft K.

The spark plug D is placed in a pocket 45 in the cylinder head. During three-quarters of a revolution of the valve the pocket is closed by the valve and therefore for this period of time it is not in communication with the interior of the cylinder. By this means the spark plug is protected, more or less, from destructive effects of 50 crustation, oxidation, or other deleterious agencies.

Having described my invention, what I claim is:

1. In an engine of the character described, 55 provided with a plurality of rotatable cylinders; an axially arranged rotatable valve

for each cylinder, having a part extending through the cylinder head; means secured to said part, outside of said head and rotatable on an axis coaxially arranged with 65 that of the cylinder, having as many projections as there are single strokes in each cycle of operation of the engine, and a suitable number of relatively stationary means in the path of said valve-rotating means, for cyclically moving said valves in piston-timed relation.

2. In an engine of the character described, provided with a plurality of radially disposed, rotatable cylinders; a hollow, axially-disposed, tapered cylinder head, fixed to the outer end of each cylinder; a hollow tapered valve in each head; a hub projecting from said valve through said head; a spring pressed plate secured to said hub 80 having as many projections as there are single strokes in each cycle of operation of the engine and an appropriate number of relatively stationary plate-rotating means, in the path of said projections, to 85 rotate each valve in proper cyclic time.

3. In an engine of the character described, provided with a series of four radially-disposed bodily-rotatable cylinder heads; a hollow cylindrical valve, axially disposed in 90 each head, and having a single valve port to coöperate with two like ports through the wall of said head, the latter being located 90 degrees apart, a spark plug located in a pocket in said head, opposite said intake 95 port; a plate secured to each valve for rotating the valve intermittently and relatively stationary means, engaged by the plates in the rotation of the cylinders, to 100 rotate each valve one-half revolution on each revolution of the cylinder structure.

4. In an engine of the character described a bodily rotatable cylinder; a cylinder head having a tapered bore and secured to one end thereof; a hollow, tapered 105 valve in said bore; a plate secured to the valve, having an axially concentric groove with spaced apart depressions; spring pressed balls engaging said groove and depressions to hold the valve in predetermined 110 position, and to yieldingly hold the valve in said bore, and an adjustable, relatively stationary means to intermittently rotate said plate, upon the rotation of said cylinder.

In testimony that I claim the foregoing, I have hereunto set my hand this fourth day of October, A. D., 1917.

JOSEPH ZANALETTI.
